UNITED STATES PATENT OFFICE.

HENRY H. MCFARLANE, OF EXTENSION, BRITISH COLUMBIA, CANADA.

RAIL-JOINT.

1,097,555.

Specification of Letters Patent. Patented May 19, 1914.

Application filed August 8, 1913. Serial No. 783,801.

To all whom it may concern:

Be it known that I, HENRY H. MCFARLANE, a citizen of Canada, residing at Extension, in the Province of British Columbia and Dominion of Canada, have invented new and useful Improvements in Rail-Joints, of which the following is a specification.

This invention relates to rail joints or means for connecting the meeting ends of railway rails, the object being to provide a simple, inexpensive and reliable form of connection for holding the rails against longitudinal, vertical and lateral movements, and which adapts the rail ends to be readily coupled or uncoupled.

The drawings, accompanying the specification, illustrate a satisfactory reduction of my improvement to practice, and in the drawings: Figure 1 is a side elevation of the meeting ends of adjoining rails constructed and connected in accordance with my improvement, Fig. 2 is a horizontal sectional view on the line 2—2 of Fig. 1, Fig. 3 is a transverse sectional view on the line 3—3 of Fig. 1, Fig. 4 is a similar sectional view on the line 4—4 of Fig. 1, Fig. 5 is a view illustrating the manner of assembling or connecting the rail ends, Fig. 6 is a perspective view of one of the rail ends, and Fig. 7 is a similar view of the co-acting rail ends.

The rails R—R' are of the ordinary construction. The rail R has its base flange cut away from its web to provide a shoulder 1, its web 2 terminating intermediate the shoulder 1 and the end of the head. The web extension 2 has its lower edge arranged a suitable distance below the juncture of the base flange with the web proper to provide what I will term a tongue 5, and the underface of the head 3 from the end of the web extension is centrally and longitudinally depressed to provide a channel 6. The web extension 2 has one of its sides integrally formed with a longitudinally extending plate 7 which terminates flush with the end of the head 2, and this plate is either bent or is formed upon its inner face with an inwardly or rearwardly extending member 8, to provide a hook.

The rail R' has its base 9 extending a suitable distance beyond its web 10, and the said web terminates a suitable distance beyond its head 11. The upper portion of the web extension 10 is projected to within the head,

that is, the said upper portion is disposed above the juncture of the head with the web, thus providing the said upper edge of the web with what I will term a tongue 12. The upper face of the base extension 9 is centrally provided with a channel 13 which extends longitudinally of the said base to the end of the web 10. The web 10 has either connected thereto or integrally formed therewith a rearwardly extending plate 14 which is arranged upon one side of said web and which extends toward the terminal of the head of the rail and which is spaced a slight distance from the web extension 10. The plate 14, thus provides what may be termed a hook, and the said hook is adapted to be engaged by the said hook provided by the members 7 and 8 of the rail R.

It is to be understood that the terminal shoulders provided by the heads, webs and base flanges of one of the rails are spaced corresponding with those of the terminal shoulders of the adjacent or co-operating rail, and in assembling the rails, the rail R has its end raised above the end of the rail R', and is lowered upon the said rail R' until its hook engages with the hook provided by the plate 14 of the rail R', and a further movement of the rails toward each other brings the tongue 12 of the rail R into engagement with the channel 6 of the head extension 3 of the rail R, and the tongue 5 of the web 3 is received within the channel 13 of the base extension 9. When the rail ends are thus connected it will be noted that the same are effectively secured against longitudinal, vertical or lateral movement, but if desired, a bearing plate 15 may be disposed upon the ties and connected with the longitudinal edges of the webs of the rails at the joint of the rails.

Having thus described the invention, what I claim as new is:

In a rail joint, two rails, one of said rails having its web at its end projecting beyond its base and its head projecting beyond its web, the web being extended below the top of the base to provide the web extension with a tongue, the head extension having its under face centrally channeled, one side of the rail being formed with a hook which extends parallel with the web of the rail, the second rail having its head terminating to the rear of its head and its web terminating to the rear of its base flange, the base flange

extension having a channel, the web having its upper edge extending upward to provide a tongue, one side of the web extension being provided with a plate which is spaced from the said web extension, the said plate adapted to be engaged by the hook of the first mentioned rail, and the tongues of the webs of the said rails adapted to be received

within the channels of the head and base flange of the co-acting rail.

10

In testimony whereof I affix my signature in presence of two witnesses.

HENRY H. McFARLANE.
